D. M. TAGGART,
TELEPHONE EXCHANGE SYSTEM,
APPLICATION FILED SEPT. 4, 1919.

1,393,465.

Patented Oct. 11, 1921.

by

Inventor:
Dawson M. Taggart.
R. R. Abbott, Atty.

UNITED STATES PATENT OFFICE.

DAWSON M. TAGGART, OF EAST ORANGE, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,393,465.

Specification of Letters Patent.

Patented Oct. 11, 1921.

Application filed September 4, 1919. Serial No. 321,704.

To all whom it may concern:

Be it known that I, DAWSON M. TAGGART, a citizen of the United States, residing at East Orange, in the county of Essex and 5 State of New Jersey, have invented certain new and useful Improvements in Telephone-Exchange Systems, of which the following is a full, clear, concise, and exact description.

10 This invention relates to telephone exchange systems, but more particularly to such systems in which common battery and local battery telephone lines terminating at a central office may be interconnected indiscriminately.

15 The object of the present invention is the provision of improved signaling means for telephone systems of this character.

20 In accordance with the object of this invention a universal link circuit is provided with a signaling device operative in one manner to give a disconnect signal from a line of either character and operative in a different manner to give a recall signal from a line of 25 either character.

25 The invention will be more clearly understood when considered in connection with the following description taken in conjunction with the accompanying drawing which 30 forms a part thereof.

35 There are shown in the drawing a common battery telephone line A and a local battery or magneto telephone line B terminating at a central office at which is located a universal cord circuit C for interconnecting telephone lines of the types represented by the lines A and B.

40 The subscriber at the station on telephone line A desiring to converse with the subscriber at the station on telephone line B removes the receiver from the switch-hook causing the energization of line relay 4 and the lighting of the line signal 5. The operator, observing the lighted condition of 45 this lamp, inserts plug 6 of the cord circuit C into jack 7 of the telephone line A, thereby causing the operation of cut-off relay 8, relay 9 and marginal relay 10 over a circuit extending from battery, through the left-hand winding of relay 9, winding of marginal relay 10, sleeve contacts of the plug 6 and the jack 7, winding of cut-off relay 8, to ground. Relay 9 in closing its contact connects a source of battery supply with the 50 winding of relay 14 through a normally 55

closed contact of the listening key 15. The operation of relay 10 disconnects the windings of relay 13 from bridged relation with the talking conductors of the cord circuit C and connects battery to the ring side of the line through the right-hand winding of relay 13 and grounds the tip side of the line so that the operation of relay 13 is controlled through the contacts of the switchhook at the station on telephone line A. Supervisory lamp 12 and relay 11 are momentarily operated upon the closure of the left-hand contact of relay 10, since this contact is closed before the opening of the normal contact of relay 13. Relay 13 in operating causes the energization of relay 14 over a circuit extending from battery, through the normal contact of listening key 15, contact of relay 9, winding of relay 14, right-hand normal contact of relay 11, alternate contact 75 of relay 13, and the supervisory lamp 12 and the right-hand winding of relay 11 in parallel to ground. Relay 11 is marginal and does not operate when included in circuit with the winding of relay 14 and when its 80 winding is shunted by the supervisory lamp 12. Relay 14 in operating completes a locking circuit for itself through its left-hand contact and the left-hand contact of relay 11.

85 The operator may now actuate listening key 15 to connect the telephone set in circuit with the telephone line. The actuation of the listening key also opens the circuit of and causes the release of relay 14. The operator, after being advised that connection 90 is desired with telephone line B inserts plug 16 of the cord circuit C into jack 17 of the telephone line B, thereby causing the operation of cut-off relay 18 over a circuit extending from battery, through the right-hand winding of relay 9, winding of marginal relay 19, sleeve contacts of the plug 16 and the jack 17, winding of cut-off relay 18 to ground. Cut-off relay 18 in operating disconnects line relay 20 from the line thereby 95 preventing the operation thereof when the party at the station on telephone line B actuates the magneto 21 to give a disconnect or a recall signal. Relay 19 is marginal and does not operate when included in circuit 100 with the high resistance winding of cut-off relay 18.

105 The operator may now restore the listening key 15 to normal position and actuate the ringing key (not shown) for connecting 110

a source of ringing current with the line for causing the operation of the call bell of station B. The restoration of the listening key 15 to normal position causes the energization and locking up of relay 14. The subscriber at B upon responding to the operation of the call bell by removing the receiver from the switchhook, is enabled to converse with the party at A without any further operation on the part of the operator.

The conversation having been completed, the parties at A and B restore the receivers to the switchhooks, the party at B giving a slight turn on the handle of the magneto 21 so that the apparatus at the central office will function to give a disconnect signal to the operator.

The restoration of the receiver to the switchhook by the party at A causes the de-energization of relay 13 which closes at its normal contact the operating circuit of supervisory lamp 12 and relay 11 which may be traced from battery through the left-hand alternate contact of relay 10, normal contact of relay 13, and the supervisory lamp 12 and the right-hand winding of relay 11 in parallel to ground. Relay 11 in operating locks up over a circuit extending from battery through the normal contact of listening key 15, contact of relay 9, winding and left-hand alternate contact of relay 14, and the left-hand winding of relay 11 to ground. The supervisory lamp 12 lights upon the closure of its operating circuit to furnish a disconnect signal to the operator denoting that the conversation has been completed.

The party at B in actuating the magneto 21 causes the energization of relay 22 as long as current from the magneto 21 is traversing the line. The closing of the alternate contact of relay 22 causes the energization of relay 23 over a circuit extending from battery through the normal contact of listening key 15, contact of relay 9, winding of relay 23, left-hand normal contact of relay 24, alternate contact of relay 22 and the supervisory lamp 25 and the left-hand winding of relay 24 in parallel to ground. Relay 23 in operating establishes a locking circuit for itself which may be traced from battery through the normal contact of listening key 15, contact of relay 9, winding and right-hand contact of relay 23 and the right-hand contact of relay 24 to ground. Relay 22, upon being deenergized, causes the lighting of supervisory lamp 25 and the energization of relay 24 over a circuit extending from battery through the left-hand contact of relay 23, right-hand normal contact of relay 26, right-hand normal contact of relay 19, normal contact of relay 22, and the supervisory lamp 25 and the left-hand winding of relay 24 in parallel to ground. The

lighting of the supervisory lamp 25 serves as a disconnect signal which is an indication to the operator that the conversation has been completed and that the plug 16 may be disconnected from the jack 17. Relay 24 in operating locks up in series with relay 23.

The operator, upon observing the lighted condition of the supervisory lamps, may remove the plugs from the respective line jacks which restores the system to normal.

Assuming now that the party at A wishes to recall the operator before the plug 6 has been withdrawn from the jack 7. The party at A removes the receiver from the switchhook which causes the operation of relay 13. Relay 13 in operating closes at its alternate contact the energizing circuit of relay 28, which may be traced from battery through interrupter 29, left-hand winding of relay 28, right-hand alternate contact of relay 11, alternate contact of relay 13, and supervisory lamp 12 and the right-hand winding of relay 11 in parallel to ground. Relay 28 in operating establishes a locking circuit for itself which may be traced from battery through the normal contact of listening key 15, contact of relay 9, right-hand contact and winding of relay 28 to ground. The locking up of relay 28 performs no useful function at this time. However, since the interrupter is now connected in circuit with the supervisory lamp 12, this lamp is intermittently lighted to give a signal of a different character than when serving as a disconnect signal in order that the operator may clearly distinguish between the two signals.

The party at B in desiring to recall the operator before the connection has been taken down turns the handle of the magneto 21 several times which causes the energization of relay 22. Relay 22 is held operated sufficiently long to cause the energization of the relay 26 over a circuit extending from battery through the contacts of the interrupter 27, right-hand winding of relay 26, left-hand alternate contact of relay 24, alternate contact of relay 22, and the supervisory lamp 25 and the left-hand winding of relay 24 in parallel to ground. A locking circuit for relay 26 is thereupon established over a circuit extending from battery through the contact of the listening key 15, alternate contact of relay 9, left-hand alternate contact and winding of relay 26 to ground. The supervisory lamp 25 is thereupon intermittently lighted over a circuit extending from battery through the contacts of the interrupter 27, right-hand winding and alternate contact of relay 26, normal contact of relay 19, normal contact of relay 22, and the supervisory lamp 25 to ground. The operator's attention is thereby directed to the flashing of this lamp.

What is claimed is:

1. A telephone system comprising com-

mon battery and local battery telephone lines, a link circuit for interconnecting said lines, and a signaling device controlled over a line of either character and operating independently of the type of connected line to furnish a disconnect signal of one character and an automatically sustained recall signal of a different character.

2. A telephone exchange system comprising common battery and local battery

10 telephone lines, a link circuit for interconnecting said lines, a signaling device in the link circuit, and means controlled over a line of either character to cause the continuous operation of the signaling device to furnish a disconnect signal and the intermittent operation of the signaling device to furnish an automatically sustained recall signal.

15 3. A telephone exchange system comprising common battery and local battery telephone lines, a link circuit for interconnecting said lines, a signaling device, means in the link circuit operative over lines of either character to cause the operation of said signaling device in one manner to furnish a disconnect signal, and a relay controlled over a line of either character and coöperating with said means to cause said signaling device to operate in a different manner to furnish an automatically sustained recall signal.

20 4. A telephone exchange system comprising common battery and local battery telephone lines, a link circuit for interconnecting said lines, a signaling device, a relay operative over lines of either character, and means controlled by said relay to cause the continuous operation of said signaling device to furnish a disconnect signal from lines of either character and to cause the intermittent operation of said signaling device to furnish an automatically sustained recall signal from lines of either character.

25 5. A telephone exchange system comprising common battery and local battery telephone lines, a link circuit for interconnecting said lines, a signaling device, a relay in the link circuit and controlled over a connected line for causing the continuous operation of said signaling device to furnish a disconnect signal, an interrupter, and a second relay controlled through the contacts of said first relay for connecting said interrupter in circuit with said signaling device for causing the intermittent operation thereof to furnish a recall signal from lines of either character.

30 6. A telephone exchange system comprising common battery and local battery telephone lines, a link circuit for interconnecting said lines, a signaling device, means for operating the signaling device in one manner to furnish a disconnect signal from lines of either character, and means for operating the signaling device in a different

manner to furnish an automatically sustained recall signal from lines of either character.

7. A telephone exchange system comprising common battery and local battery telephone lines, a universal cord circuit for indiscriminately interconnecting said lines, a relay in the cord circuit and controlled over a connected line, a second relay in said cord circuit controlled over a cord circuit conductor, and a signaling device controlled jointly by the contacts of said first mentioned and said second relay and operative upon the energization or deenergization of said second relay depending upon the type of connected line to furnish a continuous disconnect signal from a line of either character and operative in a different manner to furnish an intermittent automatically sustained recall signal from lines of either character.

75 8. A telephone exchange system comprising common battery and local battery telephone lines, a link circuit for interconnecting said lines, a signaling device, and line controlled means for causing the operation of said signaling device to furnish like disconnect signals of one character for both types of lines and like automatically sustained recall signals of another character for both types of lines.

9. A telephone exchange system comprising a plurality of local battery telephone lines, a link circuit for interconnecting said lines, a signaling device, and means in the link circuit controlled over the line for causing said signaling device to furnish a signal of one character for disconnect and an automatically sustained signal of another character for recall.

100 10. A telephone exchange system comprising common battery and local battery telephone lines, a link circuit for interconnecting said lines, a signaling device controlled over a line of either character and operating independently of the type of connected line to furnish a disconnect signal of one character and a recall signal of another character, and means associated solely with said link circuit and independent of the connected lines for discontinuing the recall signal.

105 11. A telephone exchange system comprising common battery and local battery telephone lines, a link circuit for interconnecting said lines, a signaling device, a relay in the link circuit and controlled over a connected line, a second relay associated with said first mentioned relay and operative only when said link circuit is associated with one predetermined type of said lines, a plurality of interconnected relays associated with said signaling device, an interrupter, means for controlling jointly through the contacts of said link circuit relay and said second relay

said plurality of interconnected relays and said signaling device to furnish a continuous disconnect signal, and for including said interrupter in circuit association with said 5 signaling device to furnish an intermittently operated recall signal, and means associated solely with said link circuit and independent

of the connected lines for discontinuing the recall signal.

In witness whereof, I hereunto subscribe 10 my name this 29th day of August, A. D. 1919.

DAWSON M. TAGGART.
